US00D350201S

United States Patent [19]

Hirsch et al.

[11] Patent Number: Des. 350,201

[45] Date of Patent: ** Aug. 30, 1994

[54] EXTERNAL RETAINING DEVICE FOR A FEEDING TUBE

[75] Inventors: William H. Hirsch, Columbus; Donald J. Goldhardt, Grove City, both of Ohio

[73] Assignee: Abbott Laboratories, Abbott Park, Ill.

[**] Term: 14 Years

[21] Appl. No.: 197

[22] Filed: Oct. 8, 1992

[52] U.S. Cl. D24/128

[58] Field of Search 604/180; 128/DIG. 6, 128/DIG. 26, 177, 178, 179, 174; D24/112, 129, 128, 130

CLAIM

The ornamental design for an external retainer for a feeding tube, as shown and described.

DESCRIPTION

FIG. 1 is a perspective view of an external retainer for a feeding tube showing our new design;

FIG. 2 is another perspective view thereof, opposite that shown in FIG. 1;

FIG. 3 is a top plan view thereof;

FIG. 4 is a bottom plan view thereof;

FIG. 5 is a cross-sectional view taken along line 5—5 of FIG. 3; and

FIG. 6 is an end elevational view thereof;

FIG. 7 is a perspective view of a second embodiment of an external retainer for a feeding tube showing our new design;

FIG. 8 is another perspective view thereof, opposite that shown in FIG. 7;

FIG. 9 is a top plan view thereof;

FIG. 10 is a bottom plan view thereof; and

FIG. 11 is an end elevational view thereof.

FIG. 12 is a perspective view of a third embodiment of an external retainer for a feeding tube showing our new design;

FIG. 13 is another perspective view thereof, opposite that shown in FIG. 12;

FIG. 14 is a top plan view thereof;

FIG. 15 is a bottom plan view thereof;

FIG. 16 is a cross-sectional view thereof taken along line 16—16 of FIG. 14; and

FIG. 17 is an end elevational view thereof;

FIG. 18 is a perspective view of a fourth embodiment of an external retainer for a feeding tube showing our new design;

FIG. 19 is another perspective view thereof, opposite that shown in FIG. 18;

FIG. 20 is a top plan view thereof;

FIG. 21 is a bottom plan view thereof; and

FIG. 22 is an end elevational view thereof.

FIG. 23 is a perspective view of a fifth embodiment of an external retainer for a feeding tube showing our new design;

FIG. 24 is another perspective view thereof, opposite that shown in FIG. 23;

FIG. 25 is a top plan view thereof;

FIG. 26 is a bottom plan view thereof; and,

FIG. 27 is an end elevational view thereof.

UNITED STATES PATENT AND TRADEMARK OFFICE
CERTIFICATE OF CORRECTION

PATENT NO. : Des. 350,201

DATED : Aug. 30, 1994

INVENTOR(S) : William H. Hirsch, Donald J. Goldhardt

It is certified that error appears in the above-identified patent and that said Letters Patent is hereby corrected as shown below:

UNDER "DESCRIPTION"

In the description of Fig. 6, "thereof;" should be --thereof.--.

In the description of Fig. 17, "thereof;" should be --thereof.--.

Signed and Sealed this

Twenty-fifth Day of October, 1994

Attest:

BRUCE LEHMAN

Attesting Officer

Commissioner of Patents and Trademarks
